SEQUENCE CONTROL SYSTEM FOR MULTIPLE ELECTRICALLY OPERATED DISPENSING UNITS

Roger J. Daley, Fort Wayne, Ind., assignor to Bowser, Inc., Fort Wayne, Ind., a corporation of Indiana

Application February 10, 1954, Serial No. 409,501

10 Claims. (Cl. 222—76)

This invention relates to a multiple unit sequence control system. More specifically, it relates to a liquid pumping system in which a number of dispensers are served by a plurality of pumps and in which one pump is started when one dispenser is actuated, the second pump is operated when a predetermined number of dispensers have been actuated and the third pump is started when a predetermined number of additional dispensers have been actuated and in which the pumps are stopped in reverse order as the dispensers are closed down.

A principle object of the invention is to provide an electrical control system for a number of pump units which serve a multiple number of dispensers which are actuated in a variable sequence of operation.

A further object of the invention is to provide an electrical control system in which one pump or a plurality of pumps may serve one dispenser or a plurality of dispensers which are operable at will in any order of demand.

Another object of the invention is to provide electrical control means for energizing electrical mechanisms in a predetermined order as the demand increases and deenergizing them in reverse order as the demand decreases.

An important object of this invention is to provide an electrical control system for a plurality of electrical mechanisms which are responsive to the variation of current strength or amperage flowing in the circuit to start and stop the electrical mechanisms.

With the objects definitely in view, together with other objects which will appear as this description proceeds, this invention resides in certain novel features of construction, combinations and arrangement of elements as will be hereinafter described in detail in the specification, particularly pointed out in the appended claims and illustrated in the accompanying drawings which form a material part of this application and in which:

Figure 1 is a schematic wiring diagram of the electrical control system and a piping diagram for a liquid dispensing system which is controlled thereby.

Referring to the drawing, the numerals 1, 3 and 5 represent liquid pumps having their suction inlets connected to a tank 7 through the manifold 9. The pumps 1, 3 and 5 are driven by motors 11, 13 and 15, respectively.

The discharge outlet of pump 5 is connected to the dispensers 17 through line 19, gas separator 21, line 23, check valve 25, line 27, manifold 28, line 29 and a manifold 31 having branch lines 33.

The discharge outlet of pump 3 is connected to the dispensers 17 through line 35, gas separator 37, line 39, check valve 41, line 43, manifold 28, line 29, manifold 31 and branch lines 33.

2

The discharge outlet of pump 1 is connected to the dispensers 17 through line 45, gas separator 47, line 49, check valve 51, line 53, manifold 28, line 29, manifold 31 and branch lines 33.

5 The tank 7 is provided with a fill line 2 and a vent 4.

The tank 7 is, also, connected to the air separators through a gas return line 55 having branch lines 57, 59 and 61 which are connected to air separators 21, 37 and 47, respectively.

10 Each dispenser is equipped with the usual meter, control valves, sight glasses, hose, nozzle and hose hook (not shown).

Wiring diagram

15 In the power supply circuit the main 63, which represents a regular 115 volt, 60 cycle A. C. source of supply, is connected to one side of the primary winding 64 of a "Sola" constant voltage transformer 65 having a .15 kva. rating through a disconnect switch 67 and line 69. 20 The main 71 is connected to transformer 65 through switch 67 and line 73. The secondary winding 66 of transformer 65 has one side connected to the input side of a half wave selenium rectifier 75 through line 77 thereby converting the A. C. current to D. C. current. The D. C. 25 current output from the selenium rectifier 75 charges a condenser 79 having a 20 mfd. rating, through line 81, a limiting resistor 83 having a rating of 820 ohms, line 85 and line 87. The negative side of the condenser is connected to the other side of the secondary 66 of transformer 65 through line 89 and line 91. A condenser 93 having a 20 mfd. rating, is, also, charged by the current output from rectifier 75 through line 81 and line 95. The negative side of the condenser 93 is connected to the secondary 66 of transformer 65 through line 97 and line 91. The output voltage across terminals A—B is 135 volts when in operation. In the D. C. control circuit the current flows from the positive terminal A to one side of each of the manually operated dispenser switches 99 through line 85, variable resistors 101. The sets of 30 switches and resistors are connected in parallel and the resistors preferably have a resistance of 27,000 ohms in the system illustrated. Each resistor is mounted in series with a switch 99 through a branch line 103. The other sides of all dispenser switches 99 are connected to the negative terminal B through branch lines 105, line 107, 35 relay coil 109, line 111, relay coil 113, line 115, relay coil 117 and line 91. The coils 109, 113 and 117 have a resistance of 8000, 2500, 5000 ohms respectively.

In the A. C. control circuit one side of the starter solenoid 119 of the starting switch 121 is connected to main 63 through switch 67, line 69, line 123, relay switch 125, line 127. The other side of the solenoid 119 is connected to main 71 through switch 67, line 73 and line 129.

40 The starter solenoid 131 of the starting switch 133 is connected to main 63 through switch 67, line 69, line 123, line 135, relay switch 137 and line 139. The other side of the solenoid 131 is connected to main 71 through switch 67, line 73, line 129 and line 141.

45 The starter solenoid 143 of the starting switch 145 is connected to main 63 through switch 67, line 69, line 123, line 135, relay switch 137 and line 139. The other side of the solenoid 143 is connected to main 71 through switch 67, line 73, line 129 and line 141.

50 The other side of the solenoid 143 is connected to main 71 through switch 67, line 73, line 129 and line 141. The other side of the solenoid 143 is connected to main 71 through switch 67, line 73, line 129 and line 151.

55 The other side of the solenoid 143 is connected to main 71 through switch 67, line 73, line 129 and line 151. The other side of the solenoid 143 is connected to main 71 through switch 67, line 73, line 129 and line 151.

60 In an operating circuit the motor 11 is connected to main 63 through line 155, contacts 157, 159 of switch

121, lines 161, 123, 69 and switch 67. The other side of the motor 11 is connected to main 71 through line 163, contacts 165, 167 of switch 121, lines 169, 129, 73 and switch 67. The motor 13 is connected to main 63 through line 171, contacts 173, 175 of switch 133, lines 177, 123, 69 and switch 67. The other side of motor 13 is connected to main 71 through line 179, contacts 181, 183 of switch 133, lines 185, 129, 73 and switch 67. The motor 15 is connected to the main 63 through line 187, contacts 189, 191 of switch 145, lines 193, 123, 69 and switch 67. The other side of the motor 15 is connected to main 71 through line 195 contacts 197, 199 of switch 145, lines 201, 129, 73 and switch 67.

Operation

Assume that switch 67 is closed thereby providing a power supply of constant voltage of 135 volts across terminals A and B.

Closing any one of the dispenser switches 99 causes approximately 3.30 milliamperes of current to flow in the D. C. control circuit as illustrated in the chart below.

Number of dispensers actuated	Total resistance of relays 109+113 +117	Total resistance of resistors 101 which are in circuit	Total control circuit resistance Col. 2+ Col. 3	Control circuit voltage	Current in control circuit, milliamperes	Actual measured, milliamperes	Relay cut in point
1.....	15,500	27,000	42,500	135	3.17	3.30	109-125
2.....	15,500	13,500	29,000	135	4.65	4.70	
3.....	15,500	9,000	24,500	135	5.50	5.60	113-137
4.....	15,500	6,750	22,250	135	6.06	6.10	
5.....	15,500	5,400	20,900	135	6.45	6.45	
6.....	15,500	4,500	20,000	135	6.75	6.70	117-149
7-9.....	15,500	3,857-3,000	19,357-18,800	135			

In the above chart column 1 represents the number of dispensers actuated; column 2 represents the total resistance of relays 109, 113 and 117; column 3 represents the total resistance of variable resistors 101 as set in this illustration; column 4 represents the total resistance of column 2 plus column 3; column 5 represents the constant voltage across terminals A-B; column 6 represents the current in milliamperes as calculated by Ohm's law

$$I = \frac{E}{R}$$

thus omitting the inductance factor in the circuit; column 7 represents the actual measured milliamperes in the circuit and column 8 represents the stage at which the relay switches 125, 137 and 149 are closed.

The current in the D. C. control circuit value of 3.30 milliamperes is enough to cause the coil 109 to close the relay switch 125. The relay 109 which is constructed and adjusted to pull in at approximately 2.60 milliamperes, and will drop out at a value somewhat less than 2.60.

The closure of the relay switch 125 causes a flow of current in the A. C. control circuit thereby energizing the coil 119 which closes the starting switch 121.

The starting of motor 11 causes a flow of liquid from tank 7 to the dispenser being operated.

Assume that a second dispenser is placed in operation by closing another dispensing switch 99. The current load of two actuated dispensers in the D. C. control circuit will be approximately 4.65 milliamperes as illustrated in the chart because the addition of a second resistance 101 in parallel with the first reduces the total resistance of the control circuit by about 13,500 ohms. This is insufficient current to energize relay 113, which has a coil 2500 ohms in value and is constructed and adjusted so that it will pull in at approximately 5.50 milliamperes and drop out at a somewhat lower value. Therefore, only one pump will operate to transfer the liquid from the tank to the manifold 31 when two dispensers are in operation.

Assume that a third dispenser is placed in operation by closing another dispenser switch 99.

A current of approximately 5.50 milliamperes will flow in the D. C. control circuit as illustrated in the chart because the addition of a third resistance in parallel with the other two will reduce the total resistance of the circuit by an additional 4500 ohms. This is sufficient current to pull in relay 113 closing switch 137 which in turn energizes coil 131 to close the starting switch 133. The closure of switch 133 closes the operating circuit to motor 13. Thus, the second motor 13 is energized and will drive pump 3 to contribute an additional supply of liquid to manifold 31 and to the actuated dispensers.

Assume that fourth and fifth dispensers are placed in operation by closing two more dispenser switches 99. A current of approximately 6.45 milliamperes will flow in the D. C. control circuit as illustrated in the chart because the addition of two more resistors 101 in parallel with the others has reduced the total resistance of the circuit to about 20,900 ohms. This is insufficient current to energize relay 117, which has a coil 5000 ohms in value and is constructed and adjusted to pull in at approximately 6.70 milliamperes and drop out at a slightly lower value. Therefore, only two pumps will operate to transfer the liquid from the tank to the manifold 31 when four or five dispensers are actuated.

Assume that a sixth dispenser is placed in operation by closing another dispenser switch 99. A current of about 6.70 milliamperes will flow in the D. C. control circuit as illustrated in the chart for the reasons stated above. This is sufficient current to pull in relay 117 closing switch 149 which in turn energizes solenoid 143 which closes the starting switch 145. The closure of switch 145 closes the operating circuit to motor 15. Thus the third motor 15 is energized which will drive pump 5 to contribute an additional supply of liquid to manifold 31 and to the actuated dispensers.

Should additional dispensers be actuated, the resistance of the control circuit would be lowered still more resulting in a further increase in circuit amperage which would serve to hold the relays in.

Operation of the pumps will continue as long as 6 or more dispensers remain actuated. As the actuated dispensers are closed down the current in the D. C. control circuit decreases as illustrated in the chart and relays 117, 113 and 109 drop out in that order. For example, the actuated dispensers are closed down until only five are operating. The current in the D. C. control circuit decreases to 6.45 which is insufficient to keep the relay 117 energized. The switch 149 will open, which in turn will deenergize the solenoid 143 and switch 145 will open to stop motor 15 and pump 5. Motor 11 continues to run until the last actuated dispenser is closed down.

It is obvious that any practical number of motors, starting switches, relays and dispensers could be arranged with the control circuits. Also, by varying the resistors 101 the second and third motors could be cut in and out at a different sequence if desired.

For example by changing all of the resistors to a resistance of 36,000 ohms, the first relay 109 would have to respond to a current of

135

51500

or 2.62 milliamperes. The second relay being responsive to an amperage of 5.50 would pull in when fourth pedestal is energized because the amperage would be 5.84 milliamperes with four resistors 101 in parallel.

Similarly the third relay, which required 6.70 milliamperes to pull in, would be actuated when eight pedestals are actuated

$$\frac{135}{20000} = 6.75 \text{ milliamperes}$$

By changing the resistors to 18000 ohms the first relay 75 will have to respond to a current of 4.03 milliamperes

while the second relay which responds to a current of 5.50 milliamperes will be pulled in at

$$\frac{135}{24500} = 5.50$$

on the closure of the second switch 99.

The third relay which responds to a current of 6.70 milliamperes will be pulled in on the fourth pedestal which will produce a current of

$$\frac{135}{20000} = 6.75$$

It is obvious that if the relays are to be pulled in at intervals other than those stated above by way of example, the relays themselves will have to be individually adjusted or other relays having the required current characteristics will have to be substituted to secure the desired operation.

It should also be noted that as the number of relays is increased, it becomes necessary to utilize more sensitive relays because the change in amperage as successive resistors 101 are cut in becomes less and less.

It is obvious that various changes may be made in the form, structure and arrangement of parts without departing from the spirit of the invention, accordingly, applicant does not desire to be limited to the specific embodiment disclosed herein primarily for purposes of illustration; but instead, he desires protection falling fairly within the scope of the appended claims.

What I claim to be new and desire to protect by Letters Patent of the United States is:

1. In a control system for sequentially energizing a number of mechanisms, a circuit comprising a substantially constant voltage power supply, a number of operable switches connected in parallel to one side of said supply, a resistor connected in series with each switch, said resistors being connected in parallel with each other, a number of actuatable current strength responsive devices connected in series with each other and between said resistors and the other side of said power supply, said devices being constructed to be actuated in response to different current strengths in said circuit which are attained by closing different numbers of said switches at random and means responsive to actuation of each of said devices for energizing one of said mechanisms.

2. In a control system for sequentially energizing a number of actuatable current responsive devices comprising a circuit having a substantially constant voltage power supply, a number of manual operable switches, a resistor in series with each switch, said switch resistor being connected in parallel to one side of said power supply, said resistors acting to vary the current in said circuit as different numbers of said switches at random are closed, a number of actuatable current responsive devices connected in series with each other and between said resistor group and the other side of said power supply, said devices each being constructed and arranged to be actuated in response to a different current strength in said circuit.

3. In a control system for sequentially energizing a number of actuatable current responsive devices, a circuit having a substantially constant voltage power supply, a number of actuatable control means connected to one side of said power supply, means responsive to the actuation at random of different numbers of said control means for varying the current in said circuit, a number of actuatable current responsive devices connected with each other, with said control means and with the other side of said power supply, said devices each adapted to be sequentially actuated in response to a different current strength in said circuit.

4. In a control system for sequentially energizing electrical mechanisms, a circuit having a substantially constant voltage power supply, a number of operable switches

connected in parallel to one side of said power supply, means responsive to the closing of different numbers of said switches at random for varying the current in said circuit, a number of actuatable current responsive devices connected with each other, with said switches and with the other sides of said power supply, said devices adapted to be actuated in response to different current strengths in said circuit, a number of energizable electrical mechanisms and means controlled by each device when actuated for energizing one of the mechanisms.

5. In a control system for energizable electrical mechanisms comprising a combination of a circuit having a substantially constant voltage power supply, a number of operable switches connected in parallel to one side of said power supply, a means responsive to the closing of said switches at random for varying the current in said circuit, a number of actuatable current responsive devices connected in series with each other, with said switches and the other side of said power supply, said devices being each adapted to be actuated in response to a different current strengths in said circuit, a number of energizable electrical mechanisms, means controlled by each device when actuated for energizing one of the mechanisms, and means controlled by each electrical mechanism when actuated for energizing a drive means.

6. In a control system for actuatable current responsive device comprising a combination of a circuit having a substantially constant voltage power supply, a number of operable switches connected in parallel with each other and to one side of said power supply, a variable resistor connected in series with each switch, a number of actuatable current responsive devices connected in series with each other, with said resistors and switches and with the other side of said power supply, said devices adapted to be actuated in response to different current strengths in said circuit which is produced by closing different numbers of said switches at random.

7. In a control system for energizable electrical mechanisms comprising a combination of a circuit having a substantially constant voltage power supply, a number of operable switches connected in parallel to one side of said power supply, a variable resistor connected in series with each switch, all of said resistors having substantially the same resistance, a number of relays connected in series with each other, with said resistors and with said power supply, said relays adapted to be sequentially actuated in response to different current strengths in said circuit resulting from the closing of different numbers of said switches at random.

8. In a sequence control system for multiple motors, a circuit having a substantially constant voltage power supply, a number of operable switches connected in parallel to one side of said power supply, a variable resistor connected in series with each switch, a number of relays connected in series with each other, with the resistors and switches and with the other side of said power supply, said relays adapted to be actuated in response to different current strengths in said circuit, said different current strength being obtained by closing different numbers of said switches at random, means including a starter switch connected to be actuated in response to each actuated relay to close said starter switch and a motor adapted to be energized in response to each actuated starter switch.

9. In an electrical control system for a number of electrical mechanisms comprising a circuit having a substantially constant D. C. voltage power supply, a D. C. control circuit having connected to it in series, a switch and resistor group comprising a number of series coupled switch and resistor units, said units disposed in parallel in the group and a number of relays, an A. C. control circuit controlled by each relay having a starter and said relays being sequentially responsive to said D. C. control circuit as said switches are closed at random in different numbers and an operating A. C. circuit having

drive means connected to be responsive to said starters in the A. C. control circuit.

10. In a liquid dispensing system, the combination of a number of dispensers, a liquid supply means in communication with said dispensers, said liquid supply means having a number of pumps connected thereto, said pumps being connected in parallel to supply liquid under pressure to said dispensers, a motor connected to drive each pump, a substantially constant voltage power supply, a manually operable dispenser switch for each dispenser, connecting means joining all of the dispenser switches in parallel and with said power supply, said connecting means having current varying means and means se- 5 10

quentially responsive to the strength of the flow of current connected in circuit with said connecting means and power supply and operating means responsive to said current responsive means for energizing the motors.
